UNITED STATES PATENT OFFICE.

ANNA ANDERSON, OF DASSEL, MINNESOTA.

DESIGN FOR A CORK-EXTRACTOR.

50,051.

Specification for Design.

Patented Dec. 19, 1916.

Application filed October 20, 1916. Serial No. 126,800. Term of patent 14 years.

To all whom it may concern:

Be it known that I, ANNA ANDERSON, a citizen of the United States, residing at Dassel, in the county of Meeker and State of Minnesota, have invented a new, original, and ornamental Design for Cork-Extractors, of which the following is a specification, reference being had to the accompanying drawing, forming a part thereof.

The figure is a perspective view of a cork extractor showing my new design.

I claim:

The ornamental design for a cork extractor, as shown.

ANNA ANDERSON.

Witnesses:

A. N. BALDWIN,
J. E. ANDERSON.
